UNITED STATES PATENT OFFICE.

ARCHER H. HARRIS, OF BARBERTON, OHIO, ASSIGNOR TO THE CLEVELAND RUBBER CORPORATION COMPANY, OF CLEVELAND, OHIO, A CORPORATION OF OHIO.

DESIGN FOR A TIRE-TREAD.

• 54,412.

Specification for Design.

Patented Feb. 10, 1920.

Application filed September 6, 1919. Serial No. 322,205. Term of patent 14 years.

To all whom it may concern:

Be it known that I, ARCHER H. HARRIS, a citizen of the United States, residing at Barberton, in the county of Summit and State of Ohio, have invented a new, original, and ornamental Design for a Tire-Tread, of which the following is a specification, reference being had to the accompanying drawings, forming a part thereof.

In said drawing, Figure 1, is a top plan view and Fig. 2 is a transverse section.

I claim:

The design for a tire tread substantially as shown.

ARCHER H. HARRIS.

Witnesses:

E. B. GILCHRIST,
L. I. PORTER.
